UNITED STATES PATENT OFFICE

OSCAR HAMMERSTEIN, OF NEW YORK, N. Y.

TOBACCO-MACHINE.

1,137,206.

Specification of Letters Patent. Patented Apr. 27, 1915.

Application filed November 21, 1913. Serial No. 802,188.

To all whom it may concern:

Be it known that I, OSCAR HAMMERSTEIN, a citizen of the United States, and a resident of the borough of Manhattan, city, county, and State of New York, have invented certain new and useful Improvements in Tobacco-Machines, of which the following is a specification.

My invention relates to tobacco machines and has for its object to provide a machine of this type which includes a simple and effective mechanism for treating the stems of tobacco leaf, either as a part of the leaf or separate therefrom, in a manner to render the said stems readily combustible and available for use in the manufacture of cigars, and which further includes an improved booking mechanism adapted to receive the treated tobacco from the treating mechanism and book the same in an effective and continuous manner.

Other objects of my invention will appear from the description hereinafter and the features of novelty will be pointed out in the appended claims.

Reference is to be had to the accompanying drawings in which—

Figure 1 is a side elevation of my improved machine; Fig. 2 is a front elevation thereof; Fig. 3 is a plan view; Fig. 4 is a central cross-section of said machine; and Fig. 5 is a detail sectional view of a clutch used in my improved construction.

The mechanism for treating the stems of the leaf, as shown in the drawings, comprises superimposed rollers 5 and 6, the roller 5 being suitably journaled in the main frame 7 of the machine and the roller 6 being rotatably mounted in blocks 8. The blocks 8 are slidably mounted in upright guides or standards 9 located at opposite sides of the frame 7 and are thus capable of a movement lengthwise of said guides whereby the roller 6 is capable of adjustment toward and away from the roller 5.

In order that the degree of pressure exerted by the roller 6 on the roller 5 may be regulated and adjusted when necessary or desired I prefer to provide adjusting screws 10 in screw-threaded engagement with transverse members 9^a of the guides or standards 9, lock-nuts 10^a being provided for securing said screws 10 in an adjusted position. These screws 10 are preferably formed with operating heads 11 by means of which the same may be readily manipu-

lated and either simply bear against the blocks 8 or are rotatably connected therewith.

It will readily be seen with this arrangement that, as the screws 10 are actuated in one direction or the other the blocks 8 will be moved in the guides 9 and the pressure exerted by the roller 6 on the roller 5 will be regulated accordingly. The said rollers 5 and 6 in the illustrated form of my invention are operatively connected by means of pinions 12 and 13 located respectively on the roller shafts 5^a and 6^a and may be rotatably driven in any suitable manner, for instance as will be more fully described hereinafter. The rollers 5 and 6 as shown in Fig. 2 are corrugated or otherwise roughened at an intermediate point as indicated at 14 and 14^a, the said corrugated or roughened portions being relatively narrow and the remainder of the rollers 5 and 6 being preferably smooth as clearly shown in Fig. 2. In order that the corrugations or the like 14 of the roller 5 may be kept free and clean and at all times in operative condition when the machine is in use I prefer to provide a receptacle 15 adapted to contain water or other suitable liquid 16 and having its open end closed by a cap 17 provided with a tubular extension 18 preferably of angular cross-section, said cap being detachably or otherwise fastened in position on the receptacle in any suitable manner. A wick 19 or the like 19 extends through said extension 18 into the liquid 16 and is secured in position either simply by friction or in any other convenient way with one end projecting beyond said extension 18. A suitable opening 20 may also be provided in said cap 17 through which the liquid 16 may be introduced into the receptacle 15, said opening 20 being sealed for instance by means of a screw-threaded stopper 21 as shown in Figs. 1 and 4. When in its operative position the receptacle 15 is supported in an inverted position, upon a cross-bar 22 rigidly mounted on an auxiliary frame 7^a pivoted at 7^b upon the main frame 7 as shown in Figs. 1 and 4, the extension 18 being located in a recess or sleeve 23 forming part of said bar 22 with the free end of the wick 19 in wiping engagement with the corrugations or other roughened portions 14 of the roller 6.

The auxiliary frame 7^a is provided with projections 7^c adapted to rest upon the guides or standards 9 for supporting the

front end of said auxiliary frame 7^a when in its normal position as shown in Fig. 1. It is to be understood, that said wick is of sufficient width to engage the corrugated or otherwise roughened portion 14 throughout and wipe the same as the rollers are rotated. The corrugations or roughened portion 14^a of the roller 5 may be maintained in proper operative condition by means of a separate wiper or the liquid passing from the roller 6 may simply be relied on to clean said portion 14^a of the roller 5. If desired or found necessary I may also provide a suitable drip pan beneath the roller 5 for catching any drippings from the rollers 5 and 6.

The booking mechanism as shown in the present drawings of the machine, comprises a drum 24 preferably covered with felt or other cushioning material 25 whereby injury to the tobacco by direct contact with the drum surface during booking is prevented. The drum 24 is carried by a shaft 26 or is simply provided with trunnions extending from opposite end faces, the said shaft or trunnions as the case may be being journaled in arms 27 preferably connected by a cross-bar 28 to form a rigid frame as shown in Fig. 2. These arms 27 are pivoted at 29 upon the main frame 7 so that said drum 24 is capable of a swinging movement toward and away from the rollers 5 and 6 for the purpose to be more clearly described hereinafter. A pair of endless belts or aprons 30 pass around the drum 24 and around the smooth portions of the roller 5 at opposite sides of the corrugated portions 14^a thereof and further pass over rollers 31, 32 and 33 journaled on the main frame 7 and around a roller 34 and over guide-rollers 35 rotatably mounted on the auxiliary frame 7^a, the rollers 35 being provided with flanges 35^a and 35^b for maintaining said belts or aprons each in a constant path. In order that the belts or aprons 30 may at all times be maintained under tension or in a proper operative relation to the drum I conduct the said belts or aprons over a tension roller 36 preferably flanged in the same manner as the rollers 35. This tension roller 36 is journaled upon bell crank levers 37 pivoted at 38 upon the main frame 7 and connected to move in unison by means of a cross-bar or roller 39 over which the aprons 30 also pass, a rod 40 being suspended from said bell cranks by means of links 41 and serving to detachably support one or more weights 42 whereby the tension roller 36 is maintained against the said aprons 30 to keep them always under the required tension.

An intermediate relatively narrow belt or apron 30^a is located between the aprons 30 and also passes around the drum 24 and rollers 32 and 34 and over the rollers 35 and 36 between the flanges 35^b of the rollers

35 and the corresponding flanges of the roller 36. This intermediate belt 30^a does not pass around the roller 5 or over the roller 31 and is permitted to have a movement relatively to the aprons 30 under certain conditions to be explained hereinafter by means of an auxiliary tension roller 36^a journaled upon arms 37^a capable of a rocking movement on the shaft of the roller 36. In the illustration the weight of the auxiliary tension roller 36^a alone is relied upon to properly maintain the auxiliary belt 30^a under proper tension, although it will be readily apparent that additional weight 6 may be used if this is not found sufficient. A sprocket-wheel 43 is fixed upon the drum-shaft 26 and is connected by means of a sprocket chain 44 with a second sprocket wheel 45 which is secured to or forms part of a clutch member 46 loosely mounted on a driving shaft 47, rotatably mounted on the main frame 7. As shown in the drawing clutch member 46 is provided with a plunger 48 and a coil spring 49 having a tendency to move said plunger 48 outwardly relatively to said clutch member 46. This plunger 48 is maintained in its retracted position against the tension of the spring 49 by means of a member 50 pivoted at 50^a on the main frame 7 and having an inclined cam face 51 normally extending into a circumferential groove 52 formed on said clutch member 46 and engaging a lug 48^a of the plunger 48 as shown in Fig. 5. The member 50 is operatively connected by means of a link 53 with a treadle 54 pivoted at 55 on the main frame 7 and normally held in a raised position by means of a spring 56 connected with the member 50 and whereby the free end of the latter is also maintained in the groove 52. A second clutch member 57 is fixed upon the driving shaft 47 and is provided with diametrically opposite projections 58 adapted to coöperate with the plunger 48 to couple the clutch-member 46 to the member 57 and driving shaft 47 when the treadle 54 is actuated to start the machine.

If desired a tension roller 59 mounted on a member 60, pivoted at 61 on one arm 27 and under the influence of a spring 62, may be provided for taking up any slack in the sprocket chain 44, and for insuring a perfect operative adjustment thereof at all times. With the clutch mechanism and gearing so far described and shown the drum 24 is given a half revolution each time the treadle 54 is operated and is then automatically again brought to a standstill as will be more fully described hereinafter. If no other control of the drum 24 than this is desired a belt pulley 63 may be fixed upon the driving shaft 47 and may be driven from any desired source to actuate the shaft 47 and connected mechanism. Under certain conditions however it may be found of ad-

vantage to stop the rotative movement of the drum 24 at some point before the completion of each half revolution in which case the belt pulley 63 is loosely mounted in the shaft 47 and a clutch 64 may be provided which in its normal condition operatively connects the said pulley 63 with the shaft 47. This clutch 64 is controlled by means of a collar 65 slidably mounted on the shaft 47 but adapted to rotate therewith and connected with the forked end of a bell crank lever 66 pivoted at 67 upon the main frame 7. The bell crank lever 66 is connected through the medium of a link 68 with a treadle 69 pivoted at 70 upon the main frame 7 and maintained in its normally operative or raised position by means of a spring 71, the said treadle serving to actuate or release the clutch when desired in the manner which 20 will be more fully brought out farther on in the description.

The operation of the machine is as follows:—After the driving shaft 47 has been set in motion through the medium of the pulley 63 and it is desired to start the machine, the treadle 54 is depressed by foot power or otherwise to swing the member 50 on its pivot 50^a and thus withdraw the cam face 51 from the groove 52 and out of engagement with the projection 48^a. The plunger 48 having by this operation been freed from restraint will be moved outwardly under the influence of the spring 49 into the path of the projections 58 on the clutch member 57. This clutch member 57 being fast on the shaft 47, will move one of the projections 58 into engagement with the projecting plunger 48 and thus operatively connect the sprocket 45 and connected 40 mechanism with said driving shaft 47. The movement of the sprocket 45 will be transmitted to the sprocket 43 by means of the chain 44 and will thus bring about a rotation of the drum 24 and an actuation of the 45 belts or aprons 30 and 30^a, the aprons 30 in turn serving to rotate the roller 5, which latter, owing to its connection with the roller 6 through the medium of the gears 12 and 13 will thus also rotate said roller 6.

50 It is to be understood that pressure on the treadle 54 is immediately removed after the machine has been started as described so that the treadle 54 is immediately returned to normal position under the influence of the spring 56 and the cam face 51 is moved back into the groove 52 in which it is located during the actuation of the clutch member 45 as described. It will thus be seen that at the end of one complete revolution 55 of the member 45 the lug 48^a will be returned into engagement with said cam face 51 and moved back thereby to return the plunger 48 to its initial position out of the path of the projections 58 and in consequence disconnect the clutch member 46

from the clutch member 57. In this manner the rotation of the drum 24 is automatically stopped periodically, the illustrated form of my improvement as before stated showing this stoppage occurring twice during 70 each complete revolution of the drum, or in other words the drum is brought to rest at the end of each half revolution, the sprockets 43 and 45 being proportioned to secure this result. It will of course be understood that the drum 24 may be stopped at the end of longer or shorter intervals if this should be desired. If for any reason it should become necessary to bring the drum to a standstill before the automatic stoppage thereof 80 is brought about as described, the treadle 69 is depressed and maintained in this condition as long as the operator desires the drum 24 to remain at rest. The actuation of the treadle 69 will rock the bell crank 66 85 and will consequently move the collar 65 to the left in Fig. 2 and permit the arms of the clutch 64 to move toward the shaft 47 under spring action or otherwise and in consequence release said clutch 64 from operative engagement with the pulley 63. This pulley being loose on the shaft 47 will in this condition of the parts rotate idly without in any way effecting the shaft 47. As soon as the pressure is removed from the 90 said treadle 69, the spring 71 will immediately return it to normal position and through the reverse operation of the bell-crank 66 will move the collar 65 back toward the right in Fig. 2 and in consequence again 100 operatively connect the clutch 64 with the pulley 63 to again drive the shaft 47.

During the operation of the machine the tobacco leaf *a* with the stem remaining therein is introduced between the rollers 5 and 6 with the stem thereof opposite the corrugated or otherwise roughened portions 14 and 14^a and the remainder of the leaf being opposite the smooth portions of the said rollers at opposite sides of said portions 14 and 14^a. The said leaf will thus be fed between said rollers, which in addition to their other functions therefore also constitute a feeding means and the stem of the leaf will be subjected to the action of the corrugated or otherwise roughened portions 14 and 14^a and its characteristics changed to make said stem readily combustible and available for use in cigars or the like. At 110 any time during its passage between the rollers 5 and 6 the operation of the machine may be checked as before stated by simply depressing the treadle 69, in order to give the operator an opportunity to unfold or straighten out the leaf or otherwise adjust the same for proper feeding between said rollers 5 and 6. From these rollers the treated leaf *a* passes downwardly between the aprons 30 and 30^a and the felted surface 120 of the drum 24, the stem being located 125 25 of the drum 24, the stem being located 130

adjacent to the apron 30^a and the remainder of the leaf being next to the aprons 30. In this manner the leaf is finally removed from the rollers 5 and 6 and finally becomes deposited upon the drum 24 after which the movement of the drum is automatically arrested as hereinbefore set forth.

After the treadle 54 has been again actuated a second leaf is introduced and fed 10 between the rollers 5 and 6 and is finally deposited on the drum 24 in the same manner, the two leaves being located one behind the other as shown in Fig. 4. A third leaf which may now be introduced will become 15 deposited upon the first leaf on the drum, while the following and fourth leaf will become deposited upon the second, and so on, two separate bookings of treated tobacco being in this manner built up on the drum 20 24 at diametrically opposite points thereof as will be clearly apparent from an inspection of Fig. 4. As the leaf accumulates in the manner described the aprons 30 will be gradually moved away from the periphery 25 of the drum 24, the bell cranks 37 with the roller 36 swinging on the pivot 38 to allow for this movement of the said aprons. During this operation the apron 30^a will be similarly moved away from the drum by the 30 stem portions of the leaf and as these stem portions are relatively thicker than the remainder of the leaf the booking will be thicker at these points and the said apron 30^a will be at a greater distance from the 35 surface of the drum than are the aprons 30. This independent adjustment of the apron 30^a is possible owing to the fact that the rods 37^a and roller 36^a are capable of an independent swinging movement on the 40 shaft of the roller 36 and therefore permit an individual and separate yield of said apron 30^a as is also clearly indicated in Fig. 4. At the same time as the bookings increase in thickness or size the booked leaf 45 will exert a pressure on the roller 32 and also on the drum 24 and as the roller 32 is fixed against movement transversely of its axis, the said pressure will cause the arms 27 to swing on the pivot 29 and the drum 24 50 in consequence to move away from the roller 32 and rollers 5 and 6. The drum 24 thus automatically adjusts itself to accommodate books of any thickness within its range 55 of operation, the books being at all times firmly held on the drum by the aprons and the leaf consequently protected against injury. The pressure exerted by the several aprons under the influence of the weights 32 and roller 36 insure a perfect booking 60 of the leaf, which at the same time is treated to render the stems available for use in cigars and therefore avoiding the necessity for stripping said leaf. When the desired thickness of booking has been secured the auxiliary frame 7^a is raised about its pivot 65

7^b to the position shown in dotted lines in Fig. 4 or until arrested by the stop 7^d located on the frame 7 for this purpose, thus leaving the first book free to be removed from the drum, after which the drum is 70 rotated to bring the second book into a position of ready accessibility. This second book may then also be readily removed after which the auxiliary frame 7^a is swung back 75 into its normal position to again make the machine ready for further operation, the various parts automatically adjusting themselves during these manipulations. It will be seen that the tension device 59—60 permits the chain 44 to properly adjust itself 80 during the swinging of the drum 24 on the pivots 29, so as to be at all times, in proper operative connection with the sprockets 43 and 45.

It is of course to be understood that the 85 drum 24 may be so proportioned and the machine otherwise so arranged that a single book or more than two books may be piled up thereon, the illustration being only an example of my improved machine. In the 90 preferred construction as shown the drum 24 is so mounted as to have a tendency at all times to swing toward the front of the machine or toward the rollers 5 and 6 by its own weight and thus even when fully loaded 95 with booked tobacco leaf to be prevented from dropping backward toward the rear of the machine. This arrangement avoids the necessity for using springs or analogous devices for securing this result. 100

It is further obvious that the stem treating mechanism might be used independently of the present booking mechanism and for treating tobacco leaf stems alone and which have been stripped from the leaf and 105 that the booking mechanism will be apparent is also capable of independent use.

My improved machine is extremely simple in operation and construction and is easily operated or controlled by unskilled 110 labor and is not likely to become disarranged or out of order.

Various changes in the specific form shown and described may be made within the scope of the claims without departing 115 from the spirit of my invention.

I claim:

1. A tobacco machine comprising means for feeding tobacco leaf, relatively stationary bearings for said feeding means, booking means for receiving said leaf from said feeding means and automatically adjustable relatively thereto by pressure exerted by the booked leaf toward the feeding means as the booking proceeds and mechanism for 125 actuating said means.

2. A tobacco machine comprising means for feeding tobacco leaf, relatively stationary bearings for said feeding means, a rotatable booking drum adapted to receive the 130

- leaf from said feeding means, a movable support for said drum whereby the position of said drum is automatically adjusted relatively to said feeding means by pressure exerted by the booked leaf toward the feeding means as the booking proceeds and mechanism for actuating said means and drum.
3. A tobacco machine comprising means for feeding tobacco leaf, relatively stationary bearings for said feeding means, booking means for receiving said leaf from said feeding means and automatically adjustable relatively thereto by pressure exerted by the booked leaf toward the feeding means as the booking proceeds, mechanism for actuating said means and means for moving a portion of said booking means relatively to another portion thereof to permit a removal of the books of tobacco.
4. A tobacco machine comprising a pair of feed rollers, a rotatable drum adjacent to said feed rollers, a pivoted support for said drum whereby the latter is moved away from said feed rollers by pressure exerted by the booked leaf, means for actuating said drum, an apron passing around said drum and coöperating therewith for booking tobacco leaf, said apron being operatively connected with said feed rollers to actuate same and means for maintaining said apron under tension and for permitting a movement thereof away from the surface of the drum to accommodate the leaf as the booking proceeds.
5. A tobacco machine comprising a pair of feed rollers, a rotatable drum adjacent to said feed rollers, a pivoted support for said drum whereby the latter is moved away from said feed rollers by pressure exerted by the booked leaf, means for actuating said drum, a plurality of aprons passing around said drum and coöperating therewith for booking tobacco-leaf, one of said aprons being operatively connected with said feed rollers to actuate same and means for maintaining said aprons under tension and for permitting an independent movement thereof away from the surface of the drum to accommodate the leaf as the booking proceeds.
6. A tobacco machine comprising a pair of feed rollers, a rotatable drum adjacent to said feed rollers, a pivoted support for said drum whereby said drum is moved away from said feed rollers by pressure exerted by the booked leaf, an apron passing around said drum and coöperating therewith for booking tobacco leaf, said apron being operatively connected with said feed rollers, actuating mechanism, and means for operatively connecting said actuating mechanism with said drum and feed rollers and for automatically disconnecting same at the end of a predetermined period of operation.
7. A tobacco machine comprising a pair of feed rollers, a rotatable drum adjacent to said feed rollers, a pivoted support for said drum whereby said drum is moved away from said feed rollers by pressure exerted by the booked leaf, an apron passing around said drum and coöperating therewith for booking tobacco leaf, said apron being operatively connected with said feed rollers, actuating mechanism, means for operatively connecting said actuating mechanism with said drum and feed rollers and for automatically disconnecting same at the end of a predetermined period of operation and means for temporarily disconnecting said actuating mechanism before said predetermined period of operation has passed.
8. A tobacco machine comprising a pair of coöperating rollers provided with relatively narrow coöperating corrugated portions intermediate of their ends and with smooth portions at opposite sides of said corrugated portions, a drum, aprons passing around said drum and around the smooth portions of one of said rollers, an intermediate apron between said first aprons passing around said drum and adjacent to said corrugated portions, said aprons coöperating with said drum for booking tobacco, means for permitting a movement of said aprons away from the surface of said drum to accommodate the leaf as the booking proceeds, means for permitting a movement of said intermediate apron away from said drum independently of said other aprons and mechanism for actuating said drum, aprons and rollers.
9. A tobacco machine comprising a pair of coöperating rollers provided with relatively narrow coöperating corrugated portions intermediate of their ends and with smooth portions at opposite sides of said corrugated portions, a drum, aprons passing around said drum and around the smooth portions of one of said rollers, an intermediate apron between said first aprons passing around said drum and adjacent to said corrugated portions, said aprons coöperating with said drum for booking tobacco, means for permitting a movement of said aprons away from the surface of said drum to accommodate the leaf as the booking proceeds, means for permitting a movement of said intermediate apron away from said drum independently of said other aprons, mechanism for actuating said drum, aprons and rollers and means for moving a portion of said aprons away from said drum to permit a removal of the books of tobacco.
10. A tobacco machine comprising a pair of coöperating rollers provided with relatively narrow coöperating corrugated portions intermediate of their ends and with smooth portions at opposite sides of said corrugated portions, a drum, aprons passing around said drum and around the

smooth portions of one of said rollers, an intermediate apron between said first aprons passing around said drum and adjacent to said corrugated portions, said aprons coöperating with said drum for booking tobacco, means for permitting a movement of said aprons away from the surface of said drum to accommodate the leaf as the booking proceeds, means for permitting a movement of 10 said intermediate apron away from said drum independently of said other aprons,

mechanism for actuating said drum, aprons and rollers and means for cleaning the corrugated portions of said rollers.

In testimony whereof I have hereunto set 15 my hand in the presence of two subscribing witnesses.

OSCAR HAMMERSTEIN.
